UNITED STATES PATENT OFFICE.

WILLIAM H. CARROLL, OF CLOSTER, NEW JERSEY.

DESIGN FOR A LEMON-SQUEEZER.

42,499.

Specification for Design.

Patented May 14, 1912.

Application filed February 21, 1912. Serial No. 679,139. Term of patent 14 years.

To all whom it may concern:

Be it known that I, WILLIAM H. CARROLL, a citizen of the United States, residing at Closter, in the county of Bergen and State of New Jersey, have invented a new, original, and ornamental Design for a Lemon-Squeezer, of which the following is a specification, reference being had to the accompanying drawings, forming part thereof.

Figure 1 is a side view of my design. Fig.

2 is a front, elevational view disclosing the general appearance and monogram formed in ornamental characters.

I claim:

The ornamental design for a lemon squeezer, as shown.

WILLIAM H. CARROLL.

Witnesses:

FRANK M. ASHLEY,

MINNIE S. MILLER.
